UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed April 3, 1924. Serial No. 703,875.

To all whom it may concern:

Be it known that I, CHARLES C. HANSEN, a citizen of the United States, and a resident of Easton, county of Northampton and 5 State of Pennsylvania, have invented a certain Double-Drum Hoist, of which the following is a specification accompanied by drawings.

This invention relates to hoists but more 10 particularly to power driven double drum hoists, which are adapted to be driven from a common source of power.

The objects of this invention are to enable 15 two drums as for instance, the haulage drum and the tail rope drum, to be driven from a common source of power by improved means and devices which automatically disconnect one drum and connect the other drum to the driving shaft in accordance with the direction 20 of rotation of the shaft. Further objects of the invention will hereinafter appear, and the invention is shown in one of its preferred forms in the accompanying drawings, in which—

25 Figure 1 is a longitudinal sectional elevation of a double drum hoist, and

Figure 2 is a detail fragmentary section showing the arrangement of the friction plates.

30 Referring to the drawings A designates a base plate upon which the hoist is mounted and to which the end frames B are suitably connected. A shaft C is adapted to rotate in the frames B and is preferably formed 35 with suitable thrust bearings D at the opposite ends thereof. Suitable oil pockets E may be provided in the end frames B for supplying lubricant to the shaft C, and covers F are preferably provided for the 40 oil pockets E.

In this instance an electric motor G is shown mounted on a base H although it is to be understood that any suitable motor may be employed. A driving pinion J is 45 driven by the motor G and meshes with an internal gear K which is in this instance keyed to the shaft C. The pair of drums L and O are in this instance rotatable about the shaft C and bushings P may be inserted 50 between the drums L and O and the shaft C for taking up wear. In this instance, the drums are formed with suitable flanges Q to which suitable brakes (not shown) may be applied if desired. The inner surface of 55 the flanges Q are provided with ribs or

keys R and a plurality of annular plates S having grooves or key-ways T, fit over the ribs or keys R.

A main driver U preferably in the form of an annular plate, provided with a hub V, 60 in which a sleeve W is preferably cast, and engages a worm X which is in this instance formed on the shaft C. Rotation of the shaft C in one direction creates a thrust to move the main driver U in one direction 65 and upon reversal of the direction of the rotation of the shaft C, the main driver U will be moved longitudinally by the worm X in the opposite direction. One or more ribs or keys Y is in this instance formed on the outer surface of the hub V of the main driver U. A series of annular friction plates Z are preferably formed with key-ways a which are adapted to fit over the 70 keys Y. Another series of friction plates S 75 alternate with the friction plates Z between the main driver U and the drums L and O and the number of these plates may be varied as desired.

In the operation of the hoist so far described, rotation of the worm X will create 80 a thrust to move the main driver U longitudinally relative to the shaft C, in one direction or the other according to the direction of rotation of the shaft C, and thereby causes the main driver U to force the friction plates into frictional engagement with one or the other of the drums. In this manner one or the other of the drums will 85 be driven according to the direction of rotation of the driving shaft C. The main driver U forces the alternate plates S and Z into frictional engagement with each other and thereby positively connects one or the other of the drums L and O to the shaft C. 90 When one of the drums is being driven, the other drum is adapted to rotate independently thereof. Suitable cables b and c are wound about the drums L and O respectively for haulage or other purposes. 95

In order to exert a braking or checking effect upon the drums to prevent the cables b and c from being unwound too rapidly from the drums L and O respectively, guide sleeves d are secured to the end frames B and plungers e are slidable in the guide sleeves. Brake shoes f are connected to the plungers e and are provided with brake linings g, which are adapted to bear against 100 the sides of the drums L and O to exert a 105 110

checking or braking effect thereon. Suitable springs *h* located between one end of the plungers *e* and an adjusting plug *j* constantly force the plungers *e* outwardly from the guide sleeves *d* against the sides of the drums.

I claim:

In a hoist, the combination of a frame, a rotatable shaft, a motor connected to operate said shaft, two drums rotatable about said shaft, a worm on said shaft, a main driver in engagement with said worm adapted to be moved longitudinally relative to said shaft

in one direction or the other in accordance with the direction of rotation of said shaft, 15 a series of friction plates carried by said main driver, and a second series of friction plates carried by said drums alternating respectively with the plates on said driver, the two series of plates being adapted to be 20 forced together by said main driver to drive one or the other of said drums according to the direction of rotation of said shaft.

In testimony whereof I have signed this specification.

CHARLES C. HANSEN.
